UNITED STATES PATENT OFFICE.

CLARENCE A. HILLS, OF DETROIT, MICHIGAN, ASSIGNOR TO HUDSON MOTOR CAR COMPANY, OF DETROIT, MICHIGAN, A CORPORATION OF MICHIGAN.

UPHOLSTERY.

1,218,770.

Specification of Letters Patent. Patented Mar. 13, 1917.

Application filed April 28, 1915. Serial No. 24,383.

To all whom it may concern:

Be it known that I, CLARENCE A. HILLS, a citizen of the United States, residing at Detroit, county of Wayne, State of Michigan, have invented a certain new and useful Improvement in Upholstery, and declare the following to be a full, clear, and exact description of the same, such as will enable others skilled in the art to which it pertains to make and use the same, reference being had to the accompanying drawings, which form a part of this specification.

My invention relates to upholstery and an object of my improvements is to provide an improved construction for the cushioned portion of a seat especially for the backs of seats for automobiles which shall maintain its shape and obviate the necessity of tufting.

I secure this object in the device illustrated in the accompanying drawings in which—

Figure 1 is a sectional elevation of an apparatus embodying my invention and so much of a seat as is necessary to show its connection therewith.

Fig. 2 is an elevation looking at the plane of the cushion surface, the covering material being cut away to show the internal construction.

Fig. 3 is a detail view partly broken away and having parts removed to show the construction and illustrate the mode of assembly.

Fig. 4 is a sectional elevation of a single sustaining spring and its adjacent parts.

Figs. 5 and 6 are detail sectional views illustrating a mode of construction.

Fig. 7 is the horizontal portion of the seat and b is the frame of the back of the seat. c is a strip of metal extending with its edges in a vertical plane and secured to the frame b by nails c¹, the upper end of said strip being bent to conform to the upper cross piece of the frame b. There are a series of strips c closely adjacent and parallel to each other and forming practically a continuous surface at the inner portion of the frame b, as indicated in Fig. 2.

d are coil springs extending at right angles from a strip c, as shown in Figs. 1 and 4. The inner coil of each of the springs d is secured to a strip c by lugs c² struck out

of material of said strip and bent over the 55 coil, as shown to an enlarged scale in Figs. 5 and 6. There are four such lugs to each of the springs d, as shown in Fig. 3.

f is a strip formed of a single continuous wire bent into loops having parallel sides 60 which are of equal length and normally in a single plane. A single strip f rests upon the outer ends of the springs d which extend from a single strip c.

The portion of the wire of which the strip 65 f is composed which comes at the center of the outer coil of a spring d is bent downward, as shown at f³.

A loop c² is struck up from the metal strip c at the part thereof that comes at the 70 center of the inner coil of each of the springs d.

A string e is tied at one end to each of the loops c² and at the other end to a loop f³. The strings e position the outer ends of 75 the springs d so that the outer ends of said springs come in the desired surface, as shown in Fig. 1.

The outer coil of each of the springs d is secured by four bands f⁴ f⁴ to the wire strip 80 f, as shown most distinctly in Figs. 3 and 4, each of the bands f⁴ passing around the wire of one of the loops of the band f and around the outer coil of the spring.

There is a wire strip f above, and practically of the same width as, each of the strips c. The strips f therefore come close together at their edges and together they form a practically continuous surface. Each of the bands f terminates at its lower 90 end f¹, at a distance from the seat and is unattached and at its upper end f² it is also unattached and at some distance from the seat back or frame b.

Over the surface formed by the wire 95 strips f a sheet of textile material g is passed and over this sheet a thick integral sheet g² is placed and over this latter a finished sheet of leather or other proper material is secured.

The sheet g² may be of cotton-batting quilted between burlap to the thickness of say one-half inch.

Inasmuch as the strips f form a universally yielding surface composed of wires 105 that are close together the cover described is sufficient and will permanently retain its form and it is unnecessary to use horsehair

or other stuffing and tufting is avoided. The wires in the surface formed by the strips *f* are about $\frac{3}{8}$ of an inch apart. With these dimensions the covering material will 5 not sink between the wires to an objectionable extent.

What I claim is:

1. In a spring cushion, a plurality of upright spiral springs, a strip formed of 10 looped wire the loops being of a length approximately equal to the diameter of the outer spire of said springs, said strip passing over said spring so as to cover the outer spires thereof to form a continuous surface 15 of closely adjacent wires and sheet material passing over said strip.
2. In a spring cushion, a plurality of upright spiral springs, a strip formed of 20 looped wire the loops being of a length approximately equal to the diameter of the outer spire of said springs, said strip passing over said spring so as to cover the outer spires thereof to form a continuous surface 25 of closely adjacent wires and sheet material passing over said strip, the wires forming said loops being secured to the wire forming the outer spire of said springs at points

on opposite sides of the center line of said spires.

3. In a spring cushion, a plurality of 30 rows of upright spiral springs, a strip formed of looped wire said loops being of a length approximately equal to the diameter of the outer spires of said springs, passing over each row of said springs, said 35 strips being parallel and adjacent to each other so that they shall form a continuous surface of closely adjacent wires and sheet material passing over said strip.

4. In a spring cushion, a plurality of 40 upright spiral springs, a strip formed of looped wire the loops being of a length approximately equal to the diameter of the outer spire of said springs, said strip passing over said spring so as to cover the 45 outer spires thereof to form a continuous surface of closely adjacent wires and sheet material passing over said strip, the ends of said strip being unattached and so located that they shall have freedom of movement. 50

In testimony whereof I sign this specification.

CLARENCE A. HILLS.
